US00D676964S

(12) **United States Design Patent**
Way et al.(10) **Patent No.:** US D676,964 S
(45) **Date of Patent:** ** Feb. 26, 2013(54) **TISSUE MODIFICATION DEVICE**(75) Inventors: **Bryce Way**, San Jose, CA (US); **Alberto Cantu**, San Francisco, CA (US); **Minh Tran**, Fountain Valley, CA (US)(73) Assignee: **Vertos Medical, Inc.**, Aliso Viejo, CA (US)(***) Term: **14 Years**(21) Appl. No.: **29/378,348**(22) Filed: **Nov. 3, 2010**

(57) **CLAIM**

The ornamental design for a tissue modification device, as shown and described.

DESCRIPTION

FIG. 1 is a perspective view of the tissue modification device of the present invention showing the new design; FIG. 2 is a top plan view thereof; FIG. 3 is a front elevational view thereof; FIG. 4 is a right side elevational view thereof; FIG. 5 is a left side elevational view thereof; FIG. 6 is a rear elevational view thereof; FIG. 7 is a bottom plan view thereof; FIG. 8 is a bottom perspective view thereof; and, FIG. 9 is an enlarged rear perspective view thereof.
